BENDING APPARATUS

Socrates H. Kapelis, El Cerrito, Calif.

Application March 10, 1945, Serial No. 582,073

4 Claims. (Cl. 153—48)

1

The invention relates to a bending apparatus including a plate or table, a laterally rigid template member against which a bar or the like is to be shaped by bending while resting on the plate, and a pin constructed to be mounted on the plate and to provide a backing for the template member.

A primary object of the invention is to provide an improved pin structure which is arranged to present its template-engaging head portion at different adjusted distances from the axis of the stem portion of the pin which is engaged in a socket or hole of a bending plate.

Another object is to provide for a ready adjustment of the template-engaging head portion with respect to the stem portion of the pin.

A further object is to provide a pin structure such that the line of thrust against it may be radial to its stem axis.

The invention possesses other objects and features of advantage, some of which, with the foregoing, will be set forth or be apparent in the following description of a typical embodiment of the invention, and in the accompanying drawings, in which:

Figure 1 is a plan view showing stake pins embodying the present invention in cooperative use in sockets of a bending plate.

Figure 2 is a section at the line 2—2 in Figure 1.

Figure 3 is an enlarged fragmentary section on the line 3—3 in Figure 1.

Figure 4 is a fragmentary plan view of the assembly of Figure 3.

Figure 5 is a fragmentary sectional view at the line 5—5 in Figure 3.

Figure 6 is a section at the line 6—6 in Figure 3.

As particularly shown, pins 8 embodying the features of my invention are mounted on a bending plate 9 for backing a template member 11 against the pattern edge 12 of which an initially straight bar 13 is to be shaped by bending while the table supports the template and bar. The table 9 is of a usual structure for its purpose and comprises a relatively thick plate provided with lines of holes 14 extending transversely therethrough and providing sockets for receiving the stems or bases of pins 8; in the present instance the sockets 14 are of rectangular (square) and like and uniform cross-section.

One or more thrust jacks of suitable structure may be mounted on the table 9 in appropriate position thereon for the application of their heads against a bar to be bent to conformity

2

with the pattern edge face 12 of a template 11, or another, which is disposed upon the table. As particularly illustrated, a pneumatic jack 15 has its working head 16 applied against the side or edge of a bar 13 opposite that which engages the ends of the template. Air under pressure is supplied to the jack through a hose 17 connected with a suitable source (not shown) of compressed air, and the actuation of the jack is controlled by a hand valve 18 thereof.

The base of the jack 15 is provided with a transverse hole at its rear side for complementarily receiving the shank of a headed round pin 21 to depend below the jack base. A bushing member 22 complementarily mounted in a socket 14 rotatively and fittedly receives the depending portion of the pin 21, whereby the pin provides a swiveled and anchored connection of the jack to the plate at the socket; in this manner, the jack may be adjustably swung about the pin 21 for directing the line of action of the jack head against the bar in a line which is substantially perpendicular to the bar 13 thereat. For use in the present sockets 14, the bushing 22 is provided at its upper end with an out-turned flange 22' for supporting the mounted bushing from the top of the plate.

It will now be noted that a stake pin 8 essentially comprises a stem or shank 23 hingedly mounting a head member 24 opposite an upper head-end portion 23' of the stem, and having its lower portion 23'' swiveled in a bushing member 25 which is exteriorly formed for its complementary and removable disposal in any plate socket 14. While the lower stem portion 23'' is cylindrical for its rotation in the complementary axial bore of a bushing 25, the head portion 23' of the present stem 23 is of rectangular cross-section and is at least as thick as the portion 23'' whereby it extends, at least at its corners, beyond the circle of the latter portion. In the present structure, the cross-section of the stem head portion 23' is the same as that of the bushing member 25 which receives the lower stem portion 23''.

A washer member 26 receives the stem portion 23'' therethrough and is engaged against the overhang of the head portion 23' of the stem for supporting the pin assembly from the top face of the table. As particularly shown, the washer 26 is cut away at one side in a chord line parallel to the flat upper stem portion face opposite the head member 24 to permit the swinging of the latter into close proximity to said head face while it is close to the top table face; this preferred

washer form is brought out in Figure 5. A suitable means is provided for retaining the mounted washer member for rotation with the stem 23; in the present instance, a short upper part of the stem portion 23' has a square section having its sides equal to the diameter of the remaining cylindrical part of the stem portion for effecting a rotation of the washer 26 with the stem. The washer 26 might, of course, be provided as an integral stem flange at the juncture of the upper and lower stem portions.

In order to provide for full clearance between the top of the plate 9 and the head member 24, the bushing 25 is preferably supported from the lower end of the stem portion 23'. As particularly shown, a bottom end part of the stem portion 23' is reduced and is engaged through a ring member 34 which provides a downwardly flaring bore in which the reduced stem portion is expanded for fixedly mounting the ring on the stem, as by the application of an expanding punch in an axial hole therein. In this manner, the bushing 25 is arranged for its support from the stem for the rotation of the latter therein, need not extend beyond the top surface of the plate 9, and the plate holes 14 may be of uniform cross-sections for their full lengths.

The head member 24 is hinged to the stem 23 at an axis parallel to and well above the top face of the table. As particularly shown, transversely spaced ears 27 at the top of the member 24 receive an ear 28 at the top of the stem 23 between them, and a hinge-pin 29 engaged through said ears provides the hinged connection of the member 24 with the stem 23, the axis of hinging being parallel to that face of the head portion 23' of the stem which is opposite the member 24. A bolt 31 is threadedly engaged transversely through the head portion of the stem 23 to have its free end engaged by the member 24, the other end of the bolt 31 being arranged for engagement for a turning of the bolt to adjust the angular relation of the member 24 to the stem, and so adjust the template-engaging face of the member with respect to the stem axis; in this manner, the face 32 may be variously set for the backing engagement of the template against it while the stem engages the same table socket 14. It will be understood that the previously described swiveled mounting of the stem 23 in the bushing 25 and upon the plate 9 provides for a disposal of the head face 32 substantially flat against and along the opposed edge face of the template.

In using the present stake pins 8, a template 11 is deposited in desired position upon the top of the table 8 and with its rear edge engaged against the members 24 of a pair of pins 8 which have their stems engaged in appropriately spaced sockets 14 of the table. Additional pins 8 are installed opposite the template, and their members 24 are adjusted to bear against the rear template edge with the members 24 of the first pair of pins, adjustment of any or all of the members 24 being made to provide an unyielding backing of the template by the installed pins. Having the template appropriately backed by use of the present stake pins, one or more jacks 15 are operated against a workpiece, as a bar 13, placed opposite the template face 12, to shape the bar to the template face 12 in a well-understood manner.

From the foregoing description taken in connection with the accompanying drawings, the advantages of the present device will be readily understood by those skilled in the art to which the

invention appertains. While I have described the features and principles of operation of a structure which I now consider to comprise a preferred embodiment of my invention, I desire to have it understood that the showing is primarily illustrative, and that such changes may be made, when desired, as fall within the scope of the following claims.

I claim:

1. In apparatus for bending bars and the like, a work-supporting plate, a free template member resting upon the plate, a pin extending upwardly from the plate in fixed position thereon adjacent the template member, and a head member hingedly mounted on said pin for swinging adjustment above the plate about an axis parallel to the plate and providing an upright bearing face for backing engagement with the template during the bending of a bar or the like against the template, said axis of adjustment of the head member being above the template.

2. In apparatus for bending bars and the like, a work-supporting plate, a free template member resting upon the plate, a pin extending upwardly from the plate in fixed position thereon adjacent the template, a head member hinged on said pin for swinging adjustment about an axis parallel to the plate and above the template and providing an upright forward bearing face for backing engagement by the template during the bending of a bar or the like against the template, and a thrust screw engaged through the pin below the axis of adjustment of the head and operative against the rear face of the head member for setting to adjust the spacing of the template-engaging point of the head from the pin axis.

3. In apparatus for bending bars and the like, a work-supporting plate, a free template member resting upon the plate, a pin extending upwardly from the plate in fixed position thereon adjacent the template, a head member hinged on said pin for swinging adjustment about an axis parallel to the plate and appreciably above the template and providing an upright forward bearing face for backing engagement by the template during the bending of a bar or the like against the template, and a head-adjusting means carried by the pin and adjustably operative against the rear face of the head member at a point thereof below the axis of adjustment of the head to adjust the spacing of the template-engaging point of the head from the pin axis.

4. A structure in accordance with claim 3 having the thrust point of the thrust means above the template-engaging point of the head.

SOCRATES H. KAPELIS.
